UNITED STATES PATENT OFFICE.

ROSEWELL THOMPSON, OF BRIDGEPORT, CONNECTICUT.

MACHINE FOR FEEDING WIRE.

SPECIFICATION forming part of Letters Patent No. 249,269, dated November 8, 1881.

Application filed February 18, 1881. (No model.)

To all whom it may concern:

Be it known that I, ROSEWELL THOMPSON, of the city of Bridgeport, in the county of Fairfield and State of Connecticut, have invented 5 a new and Improved Machine for Feeding Wire to Needle-Swaging Dies, of which the following is a specification with reference to the accompanying drawings.

In using the blank-feeding attachment for 10 swaging-machines for which Letters Patent were granted to me September 14, 1875, and also that patented in connection with a swaging-machine November 30, 1880, it is necessary to prepare the blanks to be operated upon by 15 the swaging-dies by first cutting the wire to the required lengths and then beveling the shank ends of the same; and it has been found advantageous in practice to also bevel the opposite end instead of leaving the sharp and irregular corner to enter the swaging-dies; and the object of my present invention is to perform 20 all these operations in connection with the swaging of the blank, and thus not only avoid considerable trouble and expense, but produce 25 a larger quantity and better quality of work than by the old method. This I accomplish by constructing a feeder in such a manner as to control a wire several feet in length, swage one end for the blade of the needle, and then 30 cut off the blank in such a manner as to leave the proper length for the whole needle and the required bevels upon the ends of the shank and wire, all of which will herein be fully explained and described.

35 In the accompanying drawings, Figure 1 is a side elevation of my improved machine. Fig. 2 is a right-end elevation, and Fig. 3 is a plan, of the same. Fig. 4 is a sectional view through the line $x-x$, Figs. 1 and 3, looking toward the 40 mechanism at the left. Fig. 5 is a sectional view through the lines $x-x$, same figures, also looking toward the mechanism at the left. Fig. 6 is a detached sectional view of the feed-spindle and devices connected therewith. Fig. 45 7 is an enlarged sectional drawing of the revolving end of the feed-spindle, so as to more clearly show and explain the manner in which it is secured to the non-revolving portion of said spindle than do the smaller drawings. 50 Similar letters of reference indicate corresponding parts.

A is a portion of the bed of a needle-swaging machine.

B is an extender, upon which is secured the base of the feeder-frame C.

55 D is the revolving end of the feed-spindle. E is the non-revolving end of the same.

$a-a'$ are the bearings for the feed-spindle.

F is a gear secured to the revolving spindle, which engages with the elongated gear G, motion being imparted to the latter by means of the train of gears H I J.

K is a shaft fitted to revolve freely in bearings $b-b'$ upon the side of the feeder-frame.

60 L is a shaft fitted to revolve freely in bearings $c-c'$ at the end of the extender.

M is a shaft fitted to revolve freely in bearings $d-d'$ upon the side of the feeder-frame.

N is a shaft fitted to revolve freely in bearings $e-e'$ upon the front edge of the bed of the 70 swaging-machine.

O is a pulley secured to the end of shaft N. $f-f'$ are miter-gears secured to shafts K and N.

75 P is a worm secured to the end of shaft K, said worm engaging with and imparting motion to the worm-wheel Q, which is secured to the shaft L. R is a cam, also secured to shaft L.

$g-g'$ are miter-gears secured to shafts L and M. $h-h-i-i-j-j-k-k$ are cams secured to shaft M. S is a 80 lever secured to the end of said shaft.

T is the wire-feeding lever, the body of which is fitted to swing freely upon the vertical stationary shaft L.

U is a bar secured to the end of the non-revolving feed-spindle E.

V is a lever pivoted at the upper end to the bar U. W is a roll fitted to revolve freely upon a pin in the free end of said lever.

90 X is a screw to adjust the position of the roll with respect to bar U and cam R. A spiral spring, Y, is inserted into the end of screw X, one end of which presses against lever V, the tension of said spring being adjusted by means of the rod Z, one end of which is pivoted to lever V, the other end passing freely through a hole in the center of the screw X, and secured in its proper position by means of nut m.

100 n is the feed-clamp fitted to slide freely in an opening in the feed-spindle E, the lower portion sliding upon the extended lower half

of the sleeve *o*. The lower half of the extended portion of sleeve *o* is a part of the bushing through which the spindle *E* slides, both being made of one piece of metal; but the lower half 5 only of said bushing is extended, so as to form a trough for purposes specified. The extended portion needs no special support, it being a part of the bushing which is driven tightly in a hole of same size through the bearing. The 10 pin which passes through both jaws of clamp *n* is not necessarily smaller in lower half of clamp, as appears in the drawings, but must be driven tightly in it; but said pin must pass freely through the hole in the upper half of the clamp, 15 and the hole through the pin must be large enough to allow the wire to pass through freely, the pressure of the upper clamp upon the wire being all that is required to feed the wire through the spindles.

15 *p* is a collar secured to spindle *E*. *q* is a collar fitted to turn freely upon said spindle and against said collar *p* upon one side, the other side having cams which actuate cross-bar *r* upon the end of tube *s*. The tube *s* is made in 20 two or more parts, so that the conical point, which closes the gripping-jaws, may revolve with them, for the end which is secured to the cross-bar *r* can only have a reciprocating motion.

25 *t* is a lever pivoted at the lower end to ear *u* upon the base *C*, the upper and free end operating collar *q* by means of connection-bar *v*, the latter being operated at the proper time by means of the cams *j* and *k*.

30 *w* is a collar secured to the end of the non-revolving spindle *E*, uniting the revolving spindle to the same by means of the collar *x*, which is screwed to the revolving spindle in the manner shown in Fig. 7.

35 *y* is an elongated stud inserted into the upper end of lever *t*, upon which the forked arm of collar *q* freely slides during the forward and backward movements of the feed-spindle.

40 *z* is a portion of the body of the feed-lever *T* extending under cam *i*.

45 *1* is a spring secured at one end to the base *C*, the opposite end pressing against the under side of the body of the feed-lever *T*.

50 *2* is a spiral spring, which actuates the feed-lever when released from contact with cam *h*.

55 *3* is a screw, which regulates the amount of stroke of the feed-lever.

60 *4 4'* are the jaws which grip the wire to be swaged. The face of said jaws is roughened similarly to a screw-nut, so as to penetrate the wire, when they are closed upon it, by means of the conical point of tube *s*.

65 *5* is a lever pivoted to the end of spindle *E*.

70 *6* is a pinion fitted to revolve freely upon a stud in the upper end of lever *5*, so as to be driven by gear *H*.

75 *7* is the cutting-off mill, secured to the side of the pinion *6*.

80 *8* is a stud in the side of lever *S*, which operates lever *5* at the proper time.

85 *9* is a stud in the side of lever *S*, which operates lever *5* at the proper time.

90 *10* is a spiral spring, which actuates lever *5* when released by stud *9*.

95 *11* is a strap which is secured at one end to the

collar *p*, passes over the roll *12*, and has a weight, *13*, suspended at the opposite end.

14 is a pair of dies of a needle-swaging machine, (shown in their relative position to the feed-spindle, but of which it has not been deemed necessary to show the driving mechanism.)

In putting the machine in practical operation, a wire ten feet, more or less, in length, and of the required diameter for the shank of the needle, is passed through the center of the spindle, with the parts in position as shown in Figs. 1 and 3, the end of the wire just reaching through the gripping-jaws. Motion is now imparted to pulley *O* in the direction indicated by the arrow. Feed-clamp *n* now gripes the wire, in consequence of the pressure of lever *T* upon it, said pressure being caused by action 75 of cam *i* upon the extended portion *z* of the body of said lever. Cam *h* now swings lever *T* forward by coming in contact with a stud upon the side of the body, (shown in dotted lines, Figs. 3 and 4,) the lever *T* operating on 80 a pin in clamp *n*, carrying forward the clamp and wire which it grasps. Jaws *4 4'* are now closed upon the wire by means of cam *j*, connection *v*, lever *t*, and collar-cam *q*, the latter actuating cross-bar *r* and forcing the conical 85 point of tube *s* between the jaw-levers, as shown in Figs. 6 and 7. Immediately after the wire is thus secured by the gripping-jaws lever *T* is released from pressure upon the feed-clamp *n* by force of spring *1*, cams *h* and *i* being in such 90 a position at this time as to allow said release and cause spiral spring *2* to bring lever *T* back to its original position. Cam *R* now imparts motion to the feed-spindle, the corner *15* being in contact with lever *V* and moving said feed-spindle and parts attached to the same rapidly 95 forward until the end of the wire reaches the swaging-dies. A slower and uniform rate of speed is now imparted to the feed-spindle, during the swaging operation upon the wire by 100 means of portion *16* of said cam acting upon roll *W*, after which the feed-spindle is rapidly thrown back to the position shown in the drawings by power of weight *13*. Now the revolving cutting-off mill is brought into action by 105 means of lever *5*, stud *9* upon the side of lever *S* operating the same until the needle-blank is cut off. Spiral spring *10* now brings said mill and lever *5* back to the position shown in Fig. 110 *2*. Then cam *k* operates collar-cam *q* through connection *v* and lever *t* and releases the wire from the gripe of jaws *4 4'*. Lever *T* and feed-clamp *n* are again brought into action upon 115 the wire, and the operations repeated as above described.

The portion of the spindle at the right of collar *w* in the drawings has both a reciprocating and revolving motion when in practical operation; but the portion at the left of said collar has only a reciprocating motion, being prevented from turning by means of the pins *17 17'*, inserted into the sides, but which are allowed to slide freely upon the edge of the lower half of the extended portion of sleeve *o*.

The end of said extended sleeve also serves as a stop for collar *p* when the same is drawn back by power of weight 13 after the swaging operation upon the wire.

5 The portion 16 of cam *R* imparts a uniform rate of speed to the lever *V* and roll *W*; but the spiral spring *Y*, inserted between said lever and screw *X*, allows the feed-spindle to yield slightly during the instant of the compression of the swaging-dies upon the wire.

Thus it will be seen that I have a machine which not only avoids the use of a hopper for blanks and mechanism necessarily connected therewith, but also avoids the trouble and expense of building and using other machines to prepare the blanks for the swaging operation.

Having thus fully described my invention, I claim as new and desire to secure by Letters Patent—

20 1. In a machine for feeding wire to the dies of a needle-swaging machine, the spindles *D* and *E*, constructed with a hole through the longitudinal center of each to receive the wire, and united together at the ends in such a manner that spindle *E*, which contains the wire-feeding mechanism, may have a reciprocating motion only, and the spindle *D*, which contains the mechanism which secures the wire during the swaging operation, may have both 25 a reciprocating and revolving motion, in combination with the actuating mechanism, for the object set forth.

2. In combination with the reciprocating and revolving spindle *D* and reciprocating spindle *E*, the jaws 4 4', tube *s*, cross-bar *r*, and collar-cam *q*, operated with mechanism substantially as shown and described, for the object set forth.

3. In combination with the reciprocating and revolving spindle *D* and reciprocating spindle *E*, the feed-clamp *n*, feed-lever *T*, and cams *h* and *i*, arranged to operate substantially as shown and described, for the object set forth.

4. In combination with the reciprocating spindle *E* and feed-clamp *n*, the sleeve *o* extending under said feed-clamp, so as to serve 45 as a bottom rest for the same, and also serve as a guide to said spindle when the same is in motion, substantially as shown, for the object set forth.

5. In combination with the reciprocating spindle *E*, reciprocating and revolving spindle *D*, and cam *R*, the bar *U*, lever *V*, screw *X*, and spiral spring *Y*, all arranged to operate substantially as shown and described, for the object set forth.

6. The combination of the hollow spindle *D*, jaws 4 4', hollow tube *s*, gear *F*, elongated gear *G*, and train of gears *H I J*, all arranged substantially as shown and described, for the object set forth.

7. In combination with the reciprocating and revolving spindle *D* and jaws 4 4', the revolving milling-cutter *S* and mechanism for imparting motion to the same, and arranged in such a relation to said spindle and jaws that 65 the wire may be cut off by said milling-cutter after the swaging operation upon the wire, for the object set forth.

8. In combination with the milling-cutter *S*, the pinion 7, lever 5, adjustable stud 9, and lever *S*, all arranged to operate substantially as shown and described, for the object set forth.

9. In combination with the collar-cam *q* and spindles *E* and *D*, the lever *t*, connection *v*, and cams *j* and *k*, all arranged to operate substantially as shown and described, for the object set forth.

ROSEWELL THOMPSON.
